UNITED STATES PATENT OFFICE

2,448,758

DENTAL ENGINE HAND PIECE

Robert C. Angell, Prince Bay, N. Y., assignor to
The S. S. White Dental Manufacturing Company, a corporation of Pennsylvania

Application September 22, 1944, Serial No. 555,245

7 Claims. (Cl. 32—26)

1

My invention relates particularly to that class of handpieces that are adapted to be employed in connection with dental engines and in which the rotating parts include chuck mechanism that is arranged to detachably engage drills, burs, grinding tools, and such implements as are commonly employed in the practice of dentistry, and in which the tool actuating parts are belt driven and the assembly is generally known as an all-cord handpiece.

The principal objects of my invention are to provide a dental engine handpiece having a slip-joint connection between its operative or driven section and its driving section whereby they may be relatively separated by axially pulling them apart to readily facilitate sterilization, replacement and substitution.

Other objects of my invention are to provide a dental engine handpiece embodying a readily separable slip-joint structure with exteriorly disposed adjusting means conveniently accessible for manipulation, whereby the tool engaging chuck may be actuated to engage and release said tool.

My invention comprehends a dental engine handpiece having a composite tool-driving hollow spindle comprising relatively separable aligned connectable spindle sections which may be axially drawn apart and replaced, but when relatively engaged rotate together as a unit.

Further objects of my invention are to provide a slip-joint connection between the operative handpiece proper and the driving elements including the driving belt pulley and its supporting structure which remain attached to the wrist joint structure with the driving belt intact while the operative handpiece proper is withdrawn, and with which supporting structure a straight handpiece, angle handpiece or contra-angle handpiece may be interchangeably connected or disconnected by an axial push or pull motion respectively with equal facility.

The form of my invention as hereinafter more specifically described comprises a dental engine handpiece having a casing or sheath which is arranged for axial engagement with and withdrawal from a wrist-joint frame, being retained therewith by a readily releasable detent latch, and which includes a separable driven section of a composite rotary tool actuating spindle, having means engageable with a cooperative driving spindle section mounted for rotation in said frame, whereby said spindle sections are caused to rotate together but being capable of relative separation by an axially directed pull ex-

2

erted oppositely to withdraw said sheath and its contained parts, when thus released by said detent.

My invention also includes all of the various novel features of construction and arrangement as hereinafter more definitely specified.

In the accompanying drawings Figure 1 is a side elevational view of a handpiece constructed in accordance with my invention, shown attached to the wrist-joint connection or support; Fig. 2 is a side elevational view of the said wrist-joint connection as it appears when the handpiece proper has been removed; Fig. 3 is a side elevational view of the thus removed handpiece proper; Fig. 4 is a side elevational view of the chuck actuating rod which projects from the right hand end of the handpiece illustrated in Fig. 3, but shown as rotated one-eighth turn from the position illustrated in said Fig. 3; Fig. 5 is an enlarged central vertical longitudinal sectional view of the handpiece structure shown in Fig. 1, without the wrist-joint therein illustrated, certain parts being shown in elevation for convenience of illustration; Fig. 6 is a transverse vertical sectional view taken on the line 6—6 in Fig. 5; Fig. 7 is a transverse vertical sectional view taken on the line 7—7 in Fig. 5; Fig. 8 is a perspective view of the forward section of the slip-joint spindle shown in Fig. 5; Fig. 9 is a perspective view of the complementary rearwardly disposed section of said slip-joint spindle as shown in the handpiece assembly illustrated in Fig. 5; Fig. 10 is a rear end elevational view of the handpiece assembly illustrated in Fig. 5, as viewed from the right hand end of said figure; Fig. 11 is a perspective view of the tool engaging chuck shown assembled in Fig. 5; Fig. 12 is a side elevational view of the semi-annular adjusting nut washer which embraces the rear end region of the slip-joint spindle shown in Figs. 5 and 9 and is engaged in the annular groove, as therein depicted; Fig. 13 is a transverse vertical sectional view taken on the line 13—13 in Fig. 5; Fig. 14 is an enlarged central vertical longitudinal sectional view of a contra-angle handpiece conveniently embodying a slip-joint assembly constructed in accordance with my invention, certain parts being shown in elevation for convenience of illustration; Fig. 15 is an enlarged central vertical longitudinal sectional view of a right-angle handpiece conveniently embodying a slip-joint assembly constructed in accordance with my invention, certain parts being shown in elevation for convenience of illustration; Fig. 16 is an enlarged fragmentary side elevational view of the

rear end portion of the rear section of the chuck actuating rod shown in Figs. 3, 4 and 5; Fig. 17 is an enlarged front elevational view of the chuck actuating rod thumb-nut illustrated in Figs. 5, 14 and 15; and Fig. 18 is an enlarged vertical longitudinal sectional view of the thumb-nut shown in Fig. 17, taken on the line 18—18 in said figure.

In said figures, the wrist-joint frame 1 is provided with the hollow supporting swivel post 2 which is swivelly engaged with the wrist-joint structure 3 of well known construction, and said frame 1 also has the forwardly projecting flanged sleeve 5 serving as a frame hub and affording a bearing for the rearwardly disposed tool driving spindle section 6, and having its radially extending flange 7 embedded in the countersunk recess 9 in said frame 1.

The spindle section 6 is provided at its forward end with the radially extended flange 10 affording a shoulder 11 which bears against the forward end of the sleeve 5, and from which flange 10 forwardly extending relatively parallel jointed projections or prongs 12 extend forwardly.

Said spindle section 6 is provided near its rearward end with the driving cord pulley 13 conveniently secured thereto by the set screw 15, and said spindle section has the circumferential groove 16 in which the semi-annular adjusting nut washer 17 is engaged to axially retain the relatively rotatable thumb-nut 19 with its threaded collar 20 in its predetermined axial position on said spindle section 6.

The structure thus described in detail represents the parts that are retained with the wrist-joint mechanism and from which the handpiece proper may be readily disengaged normally for sterilizing purposes, or for substitute replacement.

The readily detachable structure of the handpiece, or what for convenience may be termed the handpiece proper, includes the base member or back sleeve block 21 which is preferably annular and provided with the rearwardly projecting pin 22 having the detent engaging notch or depression 23 with which the cupped spring detent plunger 25 may engage and be forced to bear against its angularly directed wall to retain said block 21 in engagement with the forward face 26 of the frame 1.

Said detent plunger 25 is mounted to reciprocate in the bore 27 and is opposed by the cupped latch spring screw 29 which is screw-threadedly engaged in said bore 27 and between which and said reciprocatory detent plunger 25 is interposed the coiled expansion spring 30 tending to force the point of the detent plunger into the notch 23 against its rearward most inclined wall.

Said back sleeve block 21 carries the forwardly extending bearing sleeve 31 which is screw-threadedly engaged therewith and which has the radially extending externally screw threaded flange 32 with which the union nut 33 may be engaged by the screw threads 35, as shown in Fig. 5.

The union nut 33 is provided with the knurled band 36 by means of which it may be conveniently rotated, and is further provided with the internal screw threads 37 with which the relatively cooperative externally screw-threaded split bearing adjusting nut 39 may be engaged for relative axial adjustment.

With further reference to Fig. 5, the inner plane face of said adjusting nut 39 bears against the radially extending flange 41 of the casing or

sheath 42 which includes the integrally joined ribbed and knurled barrel 43 and the nosepiece 44, the sheath members 42, 43 and 44 being conveniently joined by the solder joints 45 and 46 to form the integral sheath structure as illustrated.

The nosepiece 44 of the compositely formed sheath is tapered toward its forward end and affords a conoidal bearing 47 tapering toward its tool receiving aperture 49, and in which bearing 47 the forward similarly tapered end portion 50 of the forward tool driving spindle section 51 is journaled.

Said forward tool driving spindle section 51 includes the relatively separable rearward extension 52 which is integrally joined therewith by the cooperative screw threads 53 to form said forward tool driving spindle section structure, and said rearward extension 52 is rotatably supported in the bore 55 of the bearing sleeve 31 and has the radially extending flange 56 engaging the forward end of said bearing sleeve 31 which conveniently serves as a thrust bearing 57 therefor.

As illustrated in Figs. 5 and 7, but probably best shown in Fig. 8, the rearward extension 52 of the forward tool driving spindle section 51 is provided with the rearwardly extending pointed projections or prongs 59 which are arranged to removably interengage with the forwardly extending pointed projections or prongs 12 on the rear spindle section 6, so that when thus interengaged said spindle sections will rotate in unison.

As shown in Figs. 5, 6 and 8, the forward spindle section 51 and its rearward extension 52 are respectively provided with the transverse slots 61 and 62 whereby they may be relatively rotated, by suitably provided wrenches, with the interengaging screw threads 53 cooperating to cause the conical shoulders 63 of the rearward extension 52 to engage the correspondingly inclined conical socket 65 in the back end of the forward portion of the forward spindle section 51 to form the composite spindle section structure.

As shown in Fig. 5, the forward end of the bore 66 of the spindle section 51 is conically tapered toward the axially aligned tool receiving aperture 67 and affords a conical forward seat 68 for the longitudinally split chuck 69 through the bore 70 of which the shank 71 of the tool, which as illustrated in Fig. 1 comprises the bur 72, extends.

Referring further to Fig. 5, the split chuck 69 is normally expanded to receive the tool shank and has its opposite ends formed conical and respectively arranged to engage the conical seat 68 in the bore of the spindle section 51 and the conical seat 73 in the forward end of the follower or plunger 74 which is disposed for axial movement in the bore 66 and which is arranged to be forced forward to effect contraction of the chuck 69 by the axial adjustment of the chuck rod 75.

Said chuck rod 75 bears against the plunger 74 and is provided at its forward end with the screw threads 76 which engage the internally screw threaded forward end region 77 of the rearward extension 52 of the spindle 51 so that its rotation may effect axial movement of the chuck actuating plunger 74 to cause the engagement or release of the tool shank 71 by the chuck 69 depending upon the direction of rotation of said chuck rod.

The chuck rod 75 extends through the rearward extension 52 and rear spindle section 6 and has the squared terminal region 78 which extends through the correspondingly square aperture 79

in the rotatable thumb-nut 19, fitting snugly therein but having freedom of relative axial movement therethrough when said thumb-nut is rotated to actuate the chuck 69 by cooperation of the screw threads 16 with the threaded forward end region of the extension 52.

As shown in Figs. 17 and 18, the thumb-nut 19 is provided with the circular recess 80, the inner plane wall 81 of which is provided with a plurality of relatively intersecting conoidal recesses 82 which also intersect the walls 83 of the square aperture 79 in the thumb-nut 19, the apices of said conoidal recesses being disposed in planes extending through the corners of the square aperture 79 and the axes of said recesses being located on radii disposed away from the axis of the thumb-nut 19 at a distance somewhat less than the radius of a circle to which the flat walls 83 of the square aperture 79 are tangent.

From the foregoing, it will be obvious that when the terminal corners 84 of the chuck rod 75 engage the surfaces of the conoidal recesses 82 and further axial inward thrust of said chuck rod 75 is exerted, said corners will ride upon their respective cooperative conoidal surfaces and thus tend to rotate the thumb-nut 19 until the flat walls 83 of the square aperture 79 register with the flats of the square end region 78 of said chuck-rod 75 and thereby facilitate its free entrance therein. As a means of precaution and protection, the chuck-rod 75 is provided with the hemispheroidal knob 85 which forms a guard for the terminus of the squared end region, as is best illustrated in Fig. 16.

Referring now more particularly to the contra-angle handpiece assembly illustrated in Fig. 14, the handheld comprising the ribbed and knurled sheath 86 and its rearwardly extended ferrule 87 embracing the spindle section 6, has the sheath attachment block 88 which is provided with the projecting pin 89 having the detent engaging notch 90 arranged to be removably engaged by the detent plunger 25 to retain the inner face 91 of said sheath attachment block 88 normally against the wrist-joint frame 1.

As shown in Fig. 14, the ferrule 87 is removably engaged with the rearward end region of the sheath 86 by the screw threads 92, and the forward end of said sheath 86 has the collet 93 secured therein as by solder and to which the contra-elbow 94 of the contra-angle head 95 of well known construction and carrying the bur 96, is removably attached by the screw threads 97.

Rotatably extended through the sheath 86 and its ferrule 87 is the bur driving spindle 98 having the forwardly extended spindle stub 99 rotatably mounted in the collet 93 and having its opposite end regions respectively engaged with the spindle 98 by the pin 100 and with the driving gear 101 by the pin 102.

The inner or rear end of said bur driving spindle 98 is rotatably supported by the spindle bearing dog 103 which encircles said spindle 98 and is engaged thereon by the pin 104 and which has the rearwardly extending prongs 105 which are arranged to removably interengage with the forwardly extending prongs 12 of the rear spindle section 6.

Referring now to the right-angle handpiece assembly illustrated in Fig. 15, the handheld comprising the ribbed and knurled sheath 106 and its removably extended ferrule 107 embracing the spindle section 6, has the sheath attachment block 108 which is provided with the projecting pin 109 having the detent engaging notch 110 ar-

ranged to be removably engaged by the detent plunger 25 to retain the inner face 111 of said sheath attachment block 108 normally against the wrist-joint frame 1.

As shown in Fig. 15, the ferrule 107 is removably engaged with the rearward end region of the sheath 106 by the screw threads 112, and the forward end of the sheath 106 has the collet 113, with forwardly extending neck 114, secured thereto as by solder and to which the right-angle head 115, of well known construction and carrying the bur 116, is removably attached by the screw threads 117.

The bur driving spindle 118, having the forwardly extended spindle stub 119 which is rotatably mounted in the collet 113, is extended through the sheath 106, and said spindle stub 119 has its opposite end regions respectively engaged with the spindle 118 by the pin 120 and with the bevel driving gear 121 by the pin 122.

The inner or rear end of said bur driving spindle 118 is rotatably supported by the spindle bearing dog 123 which encircles said spindle 118 and is engaged therewith by the pin 124 and which has the rearwardly extending prongs 125 which are arranged to removably interengage with the forwardly extending prongs 12 of the rear spindle section 6.

My invention is particularly advantageous in that the driving mechanism including the frame 1 and swivel post 2 may remain intact on a supporting engine arm, of well known construction, with the driving pulley 13 in connected relation with its driving cord or belt, while the handpiece proper may be withdrawn and replaced, or the contra-angle handpiece shown in Fig. 14 or the right-angle handpiece shown in Fig. 15 may be interchangeably substituted for the straight handpiece shown in Figs. 1, 3 and 5 with equal facility.

I do not desire to limit my invention to the precise details of construction and arrangement as herein set forth, as it is obvious that various modifications may be made therein without departing from the essential features of my invention as defined in the appended claims.

Having thus described my invention, I claim:

1. A dental engine handpiece comprising a wrist-joint support, a sheath removably carried by said support, means arranged to yieldingly engage said sheath with said support, a tool actuating spindle having relatively separable complementary sections operatively connected in slip-joint relation to rotate as a unit, and respectively mounted independently in bearings in said sheath and in said support and arranged to be relatively disconnected by the axial withdrawal of said sheath from said support, tool chucking means adjustable to effect clamping and releasing of a tool, and including a chuck rod extended through and beyond said spindle and adjustably engaged therewith, and means exterior to said spindle arranged to actuate said tool chucking means to effect grip or release of said tool.

2. A dental engine handpiece comprising a wrist-joint support, a sheath removably carried by said support, means arranged to yieldingly engage said sheath with said support, a tool actuating spindle having relatively separable complementary sections operatively connected in slip-joint relation to rotate as a unit, and respectively mounted to rotate in said sheath and in said support and arranged to be relatively disconnected by the axial withdrawal of said sheath from said support, tool chucking means mounted

in said spindle adjustable to clamp and release a tool, and including a chuck rod in screw threaded engagement with the spindle and extended through and beyond the rear end of said spindle, and a thumb nut mounted for rotation on said spindle and arranged to relatively rotate said rod therein to effect grip or release of said tool.

3. A dental engine handpiece comprising a wrist-joint support, a sheath removably engaged with said support, means arranged to yieldingly engage said sheath in rigid relation with said support, a tool actuating spindle having relatively separable complementary axially aligned sections operatively connected in slip-joint relation and respectively mounted to rotate as a unit in said sheath and in said support and arranged to be relatively disconnected by the axial withdrawal of said sheath from said support, and tool clamping means mounted in said spindle adjustable to clamp and release a tool, and including a chuck-rod in screw threaded engagement with the forwardly disposed spindle section, and extended rearwardly beyond the rearwardly disposed spindle section and affording means by which it may be rotated with respect to said spindle and thereby be axially adjusted with respect thereto to effect clamping or releasing of said tool.

4. A dental engine handpiece comprising a wrist-joint support, a sheath removably engaged with said support, means arranged to yieldingly engage said sheath in rigid relation with said support, a tool actuating spindle having relatively separable complementary axially aligned sections operatively connected in slip-joint relation and respectively mounted to rotate as a unit in said sheath and in said support and arranged to be relatively disconnected by the axial withdrawal of said sheath from said support, and tool clamping means mounted in said spindle adjustable to clamp and release a tool, and including a chuck-rod in screw threaded engagement with the forwardly disposed spindle section, and extended rearwardly beyond the rearwardly disposed spindle section and affording means including a polygonal terminal region by which it may be rotated, and a thumb-nut having a polygonal aperture slidably fitted to said chuck-rod for axial withdrawal and mounted for relative rotation on said spindle but restrained from axial relative movement thereon.

5. A dental engine handpiece comprising a support, a sheath removably engaged with said support and having an end thrust bearing, means adjustable to vary the length of said sheath to effect takeup on said bearing, a tool actuating spindle terminating in said bearing and having relatively separable complementary sections operatively engaged to concurrently rotate and respectively mounted for rotation in said support and in said sheath and arranged to be relatively separated by axial withdrawal of said sheath from said support, tool chucking means including a

split chuck and follower therefor mounted in the forward section of said spindle, adjustable to engage and release an operative tool, a chuck-rod extended through said spindle in threaded engagement therewith, rotatable to adjust said chuck, and having a polygonal terminal region protruding beyond the rear end of said spindle, and a thumb-nut rotatably mounted on said spindle and having a polygonal aperture through which said chuck-rod extends for relative axial movement.

6. A dental engine handpiece comprising a support, a sheath removably engaged with said support by a snap detent connection and having an end thrust bearing, a tool actuating spindle terminating in said bearing and having separable complementary sections operatively engaged in relatively separable relation to concurrently rotate and respectively mounted for rotation in said support and in said sheath and arranged to be separated by axial withdrawal of said sheath from said support, tool chucking means including a contractable and expandable chuck and cooperative follower therefor adjustable to engage and release an operative tool, a chuck-rod extended through said spindle in threaded engagement with the forward section thereof, rotatable to adjust said chuck with respect to said tool and having its terminal region shaped to form a key projecting beyond the rear end of the rear section of said spindle, and a thumb nut rotatably mounted on the rear section of said spindle and having an aperture formed to engage said key and arranged to effect rotation of said chuck-rod but to permit its axial withdrawal therefrom upon separation of said spindle sections.

7. A dental engine handpiece comprising chuck actuating mechanism which includes a chuck actuating rod mounted for axial adjustment by rotation and having a polygonal terminal region, a relatively removable thumb-nut having a polygonal aperture through which said polygonal terminal region may be removably extended, and having a plurality of relatively intersecting recesses providing curved walls which serve as guides for directing said terminal region into said aperture.
